UNITED STATES PATENT OFFICE

SALVATORE BUCARO, OF BROOKLYN, NEW YORK, ASSIGNOR TO CONSOLIDATED
MACARONI MACHINE CORPORATION, A CORPORATION OF NEW YORK

CONVEYER FOR PRELIMINARY DRYING OF SHORT MACARONI

Application filed July 29, 1929. Serial No. 382,008.

This invention relates to new and useful improvements in machines for drying short macaroni.

The invention has for an object the provision of a device of the class mentioned which is of simple, durable construction, dependable in use and efficient in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a horizontal sectional view of a device constructed according to this invention, seen as though taken on the line 1—1 of Fig. 2.

Fig. 2 is a vertical sectional view taken on the line 2—2 of Fig. 1.

Fig. 3 is a fragmentary plan view of Fig. 2 looking in the direction of the line 3—3 of this figure.

Fig. 4 is a fragmentary horizontal sectional view taken on the line 4—4 of Fig. 2.

Fig. 5 is an end elevational view of the device, seen from the supply end.

Fig. 6 is a vertical sectional view taken on the line 6—6 of Fig. 2.

Fig. 7 is an end elevational view of the device, seen from the discharge end.

Fig. 8 is a fragmentary horizontal sectional view taken on the line 8—8 of Fig. 2.

Fig. 9 is a vertical sectional view taken on the line 9—9 of Fig. 8.

Fig. 10 is a vertical sectional view taken on the line 10—10 of Fig. 8.

Fig. 11 is an enlarged fragmentary detail view of a portion of Fig. 2.

Fig. 12 is an enlarged detail fragmentary view of a portion of Fig. 6.

The device is shown with a body consisting of a flat horizontal base 15 connected with parallel vertical front and rear longitudinal walls 16 and 17, respectively. Front and rear longitudinal partitions 18 and 19, re-

spectively are positioned between the walls and are also connected with the base. A third vertical longitudinal partition 20 connects with the base 15 and is positioned between the partitions 18 and 19, and near the 55 partition 19.

One end of the body is provided with vertical front and rear wall extensions 21 and 22, respectively, terminating a sufficient distance from the bottom of the base 15 so that a receiving truck may engage underneath. Such a receiving truck is illustrated in Figs. 2 and 7 by reference numeral 23. This end of the device may be called the discharge end. The opposite end may be called the supply 65 end. A plurality of hinged doors 24 close both ends of the body.

Conveying means is mounted within the body and consists of a top endless horizontal belt 25, a central endless horizontal belt 26 70 and a bottom endless horizontal belt 27. These belts extend the complete length of the body, that is, from the supply end to the discharge end. At the supply end, the endless belts are mounted upon wheels 28 having 75 peripheral notches 29. These wheels are supported by shafts 30 which extend into the space between the partitions 19 and 20. A bevel gear 31 is fixed upon the top shaft 30, another bevel gear 32 is adapted to drive the central shaft 30 thru gears 47 and a bottom bevel gear 33 is fixed upon the bottom shaft. The gear 31 is the largest of these three gears, 32 is of intermediate size and 33 the smallest. These gears mesh with bevel gears 34 all of 80 the same size and fixed upon a vertical shaft 35.

The conveying means is provided at the discharge end with shafts 36 supporting 90 wheels 28 with peripheral notches 29. These wheels serve to support the other ends of the endless belts. Each of the shafts 36 is mounted at each end in a pillow block 37 provided with a bottom flange 38 slidably engaged in 95 a groove 39 formed in a bracket 40. These brackets are supported upon the wall extensions 21 and 22. A screw 41 threadedly engages a portion of the bracket and rotatively connects with the pillow block, and the head 100

of the screw extends to the exterior of the device.

Each of the endless belts consists of longitudinal flexible metal strips 42, screen material 43 with turned-up edges 43' engaged upon the metal strips, transverse pipes 44 engaged beneath the metal strips and bolts 45 securing these parts together. The pipes 44 have extendable tapered ends 44' and are regularly spaced and are arranged at a distance for engaging in the notches 29 of the wheels 28. This arrangement insures the moving of the endless belts when certain of the wheels 28 are rotated. The ends 44' of the transverse pipes 44 rest upon angle irons 46 attached upon the body member of the device and provided with projections 46' for causing the belts to vibrate for shuffling the macaroni, the up-turned edges prevent the falling of the macaroni from the belts. The extendable tapered ends 44' may be adjusted for changing the tension of the belts during the vibration impulses providing for the adjustment of the strength of the impulses.

The gear 31 engages beneath its meshing gear 34 so that the endless conveyer 25 is caused to move as indicated by arrow 49. The gear 32 engages the meshing gear 34 and drives a pair of wheels 47, causing the central conveyer to move in an opposite direction, and the gear 33 engages on the bottom of its gear 34 to cause the bottom endless conveyer to move in the same direction as the top one.

A spreading means is provided for dropping a supply of macaroni upon the top conveyer and consists of a vertical bar 50 at the supply end of the body and pivotally supporting a hopper 51. The discharge end 52 of this hopper is directed over the top of the top endless belt 25. A crank arm 53 connects the discharge end of the hopper with a disc 54 formed integral with a gear 54' which meshes with a gear 35' secured upon the vertical shaft 35. This crank arm is eccentrically connected on the disc. Rotation of the shaft 35 will cause the hopper to pivotally move back and forth so as to distribute macaroni upon the top conveyer.

A draft means is provided in the body member for acting against the macaroni positioned upon the conveyers and consists of passages 55 between the partitions 18 and 19 and the walls 16 and 17, respectively. These passages are open at the top and communicate with the atmosphere. The partitions 18 and 19 are formed with a plurality of apertures 56 connecting the passages 55 with the air in the vicinity of the endless belts. The partition 20 is provided with a plurality of fan apertures 57, and fans 58 are rotatively supported in these apertures. For providing the supporting arrangement, strips 59 are provided. These strips connect with the partition 20. Each of the fans 58 is provided with a shaft such as indicated by numeral

60 and each of these shafts is provided with a pulley 61.

In operation, the passages 55 admit the warmer strata of upper air which pass between wall 17 and partition 19 and turn into apertures 56 of the partition. These apertures admit only a lateral current of air to the fans 58, thereby avoiding cross currents of air which would occur if the partition 19 were removed. The fans drive the air from side 20 to side 18 between which the macaroni is passed. After evaporating the moisture in said macaroni, the air cools and passes thru apertures in side 18 into the passage between walls 16 and side 18 and is ejected therefrom to the upper stratum of air to be rewarmed.

The device is provided with a driving means which consists of an electric motor 62 mounted upon the base 15 and connected by a belt 63 with a main shaft 64 rotatively mounted in the partitions 18 and 19. A plurality of pulleys 65 are fixed upon the shaft 64 and connect with belts connected with the pulleys 61 for driving the draft fans. Another pulley 66 is fixed upon the shaft 64 and is connected with a system of belts and pulleys for driving a worm pinion 67. This worm pinion connects with a worm gear 68 fixed upon the shaft 35.

In operation of the device, macaroni is fed into the hopper 51 and is discharged upon the top endless belt 25. Operation of the motor 62 is communicated for oscillating the hopper 51 so that the macaroni is distributed in a uniform fashion. The operation of the motor is also communicated for driving the endless belts so that the macaroni passes several times up and down the body of the machine. The bottom conveyer travels the fastest so that at the end of the draft system, the macaroni will be spread far apart and not likely to stick together. The bottom of the endless belts discharge the macaroni upon some container placed upon the truck 23. The screws 41 may be adjusted for changing the tension of the endless belts.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In a machine for drying short macaroni, a body, partitions in said body, angle irons attached thereon and provided with projections and an endless belt movably mounted in the body and consisting of flexible metal strips, screen material mounted thereon and provided with up-turned edges, transverse pipes with extendable tapered ends attached to said strips and screen and

during motion of the endless belt the tapered extensions being arranged for engaging the projections for vibrating the belt, and means for adjusting the extension of the tapered member so as to control the strength of vibration.

2. In a machine for drying short macaroni, a body, partitions in said body, an endless belt movably mounted in the body and consisting of flexible metal strips, screen material mounted therein and provided with up-turned edges, and transverse pipes with extending tapered ends attached to said strips and screen, and means for engaging said tapered ends during the motion of the endless belt for vibrating the belt.

3. In a machine for drying short macaroni, a body, partitions in said body, angle irons attached thereon and provided with projections, and an endless belt movably mounted in the body and consisting of flexible metal strips, screen material mounted thereon and provided with up-turned edges, and transverse pipes with extendable tapered ends attached to said strips and screen and during motion of the endless belt the tapered extensions being arranged for engaging the projections for vibrating the belt.

In testimony whereof I have affixed my
signature.

SALVATORE BUCARO.
